STEAM GENERATOR

George P. Jackson, Flushing, N. Y., assignor to
 Combustion Engineering-Superheater, Inc., a
 corporation of Delaware

Application August 16, 1944, Serial No. 549,719

2 Claims. (Cl. 122—411)

1

This invention relates to steam generators and particularly to those operating at high capacities and under high pressures. It is a continuation in part of my application Serial No. 499,530, filed August 21, 1943, now abandoned.

It has long been recognized in the steam generating art that there are conditions which would make it desirable to operate with forced circulation, strictly speaking, or with augmented natural circulation. In general, two difficulties have been encountered. Those installations which have been successful (considered only from the standpoint of circulation) have been inordinately costly, the cost of the pumping and circulation equipment far outweighing the savings effected in the steam generating plant proper by the use of the forced circulation, not to mention the high cost of maintenance. In other words, the cost of such installations has been much higher than the cost of an installation of the same capacity and pressure designed to secure adequate circulation by natural circulation. There have been many proposals in the art which have never gone into use because, although the cost of the circulation equipment was not excessive, they were ineffective for one reason or another. Therefore, natural circulation systems have been generally employed in high pressure boilers, despite the fact that they are very sensitive and subject to circulation interruption and overheating.

To the best of my knowledge, I am the first to provide an arrangement whereby adequate circulation can be provided not only at low cost of initial installation but also with low cost of maintenance. Stated in another way, I believe that I am the first to provide an installation with circulation equipment at a cost but very slightly in excess of the cost of an installation of the same capacity and pressure having adequate natural circulation. Moreover, in my invention the costs of maintenance are very low.

In carrying out my invention, I employ the feed water to operate the pumps for augmenting the natural circulation. I have discovered that if I combine this with a boiler operating at a pressure of substantially 900 lbs. per square inch upward (but short of critical pressure) I will be enabled to increase the circulation and secure a ratio of water to steam, such as will protect the tubes against unduly high temperatures and consequent internal stresses, while at the same time I am enabled to use much smaller tubes than would be required if natural circulation alone were relied upon, which, in turn,

2

means that the weight and the cost of the boiler installation is greatly reduced. So much so is this the case, that the cost of my improved installation, inclusive of the circulating equipment, will be only in the neighborhood of about 2% to about 2½% more than the cost of the same installation constructed on the basis of natural circulation. The advantages gained far outweigh this relatively slight increase in cost.

10 In the combination, I also employ a type of boiler in which by far the greatest portion of the steam is generated by evaporating surfaces subject to radiant heat, the amount of convection surface, if any, being relatively small so that, at best, only a relatively small portion of the steam generated is generated from surfaces subject to convection heat. The invention is practically only applicable to boilers of relatively high pressures where the heating surfaces of the furnace generate the major portion of the steam, and where the ratios of requisite water circulated to steam generated become relatively low. I have discovered that for such boilers the feed water can be economically used to drive the augmented circulation pumps efficiently.

15 In the accompanying drawings I have shown an installation, designed for approximately 1400 lbs. pressure per square inch and a capacity of about 500,000 to 550,000 lbs. of steam, as illustrative of how my invention may be employed.

20 In these drawings:

Figure 1 is a vertical section through a steam generator embodying my invention, the same being taken on the line 1—1 of Figure 2;

25 Figure 2 is a rear elevation of the steam generator, showing in greater detail, the means for augmenting the natural circulation;

Figure 3 is an enlarged vertical section through the circulator pump employed in carrying out my invention;

30 Figure 4 is a sectional view similar to that of Figure 3 but illustrating a modified form of circulation pump; and

35 Figures 5 and 6 are more or less diagrammatic views illustrating modifications of the hook-up shown in Figures 1 and 2.

40 Referring now to Figures 1 and 2, the furnace is provided with the usual fuel burners 2 (such, for example, as powdered coal, oil or gas burners) which project through the front wall.

45 The front, rear and side walls of the furnace are faced or lined with water wall tubes 3 such, for example, as 2" tubes on about 2½" centers, swaged or staggered at the bottom and the top for connection to the headers to be described.

It will be seen that these tubes are relatively small diametered, long, tubes of relatively thin wall thickness as compared with the tubes customarily employed in a natural circulation boiler of corresponding pressure. (From the floor level to the center line of the boiler is 88' 9", in the installation shown.) Assuming a pressure of 1400 lbs. p. s. i., the tubes customarily employed in a natural circulation boiler would be approximately 3" in diameter on 3 1/8" centers. The wall and roof tubes in my boiler are subject to radiant heat.

The side water wall tubes 3 are connected at their bottom ends to headers 4 and 5 which are in turn connected to the drum or large header 6 by means of tubes 7 and 8. The front and rear water wall tubes 3 are connected at their bottom ends to the drum 6. Thus drum or header 6 serves as a common supply for all of the water wall tubes.

All of the wall tubes 3 deliver into the steam and water drum 9; the front wall tubes via the radiant heat screen tubes 10 which shield the superheater 15, the rear water wall tubes via the radiant heat roof tubes 11, and the side water wall tubes via headers 12 and tubes 13.

The products of combustion leave the furnace 1 through the offtake 14 after first passing over the screen tubes 10 and the suspended superheater 15. Upon leaving the offtake 14 the combustion gases pass downwardly through flue 16 in which is suspended a superheater 17, and thence pass upwardly through flue 18 in which the economizer 19 is hung. Optionally, for reasons which will hereinafter appear, a secondary economizer or evaporator 20 may be placed in the flue 18 in advance of the economizer 19 with respect to gas flow.

Suspended from the steam and water drum 9 and connected therewith are a plurality of so-called downcomer tubes 21 which are connected to a plurality of pumps 22, as will further appear. (For this installation, four 10" tubes 21 are employed.) The pumps 22 discharge into 10" tubes 23 which are connected to the drum 6. As will further appear, the pumps 22 augment the natural circulation of the boiler producing what may be termed an augmented natural circulation boiler.

Referring now to Figure 3, the construction of the pumps 22 will now be described. This pump is hydraulically driven and comprises a turbine or an impeller wheel 24 mounted to rotate with shaft 25 within the housing 26. Peripherally surrounding the wheel 24 is an inlet volute passage 27 and axially adjacent to the wheel 24 is an outlet conduit 28. Fastened to the wheel housing 26 through the medium of flange 29 and flange 32 and bolts 30 is a pipe elbow 31. The vertical leg 33 of the elbow 31 is fitted with a sleeve 34 within which the water pump propeller 35 rotates with the shaft 25 driven by the wheel 24. A cage 36 is supported concentrically with shaft 25 by means of the flange 37 which is clamped between flanges 29 and 32. The cage 36 is so formed as to support bearings 38 and 38a which in turn position and support the shaft 25, wheel 24 and impeller 35. The free area in sleeve 34 which surrounds the impeller is relatively large. The vertical leg 33 of the elbow is connected to one of the pipes 23, and the horizontal leg to one of the downcomer pipes 21.

When fluid under pressure is delivered into the volute passage 27 it reacts on wheel 24, while flowing therethrough, causing it to rotate, after

which it is discharged through outlet conduit 28. For operational reasons which will later appear, a check valve 39 is located in the horizontal portion of elbow 31.

5 The means for supplying fluid pressure for driving the pump will now be described, reference being had to Figures 1 and 2. The boiler feed pump 48 which may be of the conventional construction ordinarily employed in feed water pumps is connected by a pipe or pipes 49 to the header 50 which is in turn connected by means of pipes 51 to the volutes 27 of each of the pumps 22. Thus the boiler feed water discharge from the feed water pump enters the volutes 27, drives the wheels 24 and leaves through the outlet conduits 28, each of which is connected by means of a pipe 51a to a common header 52. This header 52 in turn is connected by a pipe or pipes 53 with the economizer 19. Thus the feed water, after having performed its function of driving the pumps, is led to the economizer and after passing through the economizer, it flows through pipe or pipes 54 into the boiler drum 9.

Since each of the downcomer tubes 21 leads 25 to a pump 22 (specifically to the horizontal leg of the elbow 31 of each pump), the pump propellers augment the natural circulation by forcing the water in downcomers 21 into the header 6 (through pipes 23 connected to the vertical leg 33 of the elbows 31), and from header 6 through the tubes which connect the water wall tubes 3 with header 6.

Thus the boiler has augmented natural circulation. At from approximately 900 lbs. p. s. i. and upward in boiler pressure, I have found that the feed water driven pumps will augment the circulation to the point that the ratio of water to steam entering the boiler (say about 10 to 1 at 900 lbs. with decrease as pressure rises), will adequately cool the tubes. At such pressures per square inch, the pumps are so efficient that the desired results can be obtained with a feed water pump but slightly larger than would be employed where the natural circulation is not augmented. 40 In this connection, feed water pumps are designed to operate at a pressure somewhat in excess of the boiler pressure, usually somewhere about 200 lbs. in excess. For example, at 1400 p. s. i., I need a feed water pump giving about 10% higher excess than customary or about 140 p. s. i. excess.

It will be seen that the hydraulic motors, the water pump propellers, and the interconnecting drive means, are wholly contained within the fluid circuit pressure parts, as are the bearings 55 for the drive means. Inasmuch as there is greater pressure in the volutes 27 than exists in the elbow 31, the bearings will be lubricated by the feed water, which is clean. To this end the holes 24a are provided. The bearings may be made of any 60 suitable bearing metal. There are no stuffing boxes.

It will be evident that the pumps are of simple, inexpensive construction, and will have relatively long life. As stated, well known forms of feed water pumps of at most but slightly greater power than customary, may be employed. Hence it will be seen that I have provided an installation for augmenting the natural circulation, the cost of which and the maintenance costs of which are very low. This coupled with the fact that I am thereby enabled to use small diametered evaporating tubes of thin wall thickness, produces a high pressure installation of relatively low weight and cost as compared with high pressure natural circulation boilers. The use of radiant heat tubes

in the boiler which produce by far the most (or all) of the steam generated, also tends toward securing the desired results and secures high capacity. It will also be seen that my improved system overcomes the interruption to circulation incident to the ordinary high pressure natural circulation type of boilers hereinbefore referred to, and the difficulties incident thereto.

In the event that the temperature of the gases passing upwardly through flue 18 is so high that steam may occur in the lower tubes of the economizer 19, it may be desirable to include the secondary evaporating or economizer surface 20 in order to moderate this temperature and to ensure the absence of any appreciable amount of steam. Where such a secondary economizer is used, a circuit is provided from drum 9 through the evaporator and back to drum 9, as, for example, by means of pipes 56, 57 and 58 shown in Figure 2. Since the resistance of such a circuit would be relatively high, I place a circulating pump 55 in this circuit (see Fig. 2), which pump is a duplicate of the pumps 22 hereinbefore referred to. This pump 55 would be supplied with feed water for driving the motor thereof by means of pipe 59 leading from header 52, and the feed water discharged from such pump would be led to header 52 by means of the pipe 60.

Again referring to Fig. 2, a feed water regulating valve 61 is placed in the pipe 53 leading from the header 52. In order to maintain circulation by means of the pumps 22 and 55, when the feed water regulating valve 61 is partially or completely closed, I provide a relief valve 62 connected by pipe 63 to the suction side of the feed water pump 48 or to some other suitable point in advance thereof, such as to a feed water heater in advance of the feed water pump.

Since all pumps 22 run in parallel, and should one of the pumps fail to rotate, the water from drum 6 being maintained under the pressure of the remaining pumps 22, might flow upwardly through a pipe 23 and through the pump that failed, which might disturb the circulation. It is for this reason that check valve 39, hereinbefore referred to, is located in the horizontal leg of elbow 31 of each pump. Should such a reverse flow as described occur through failure of a pump, its check valve 39 would close and stop such flow.

It may be desirable to divide the interior of drum 6 into compartments 64 by means of partitions 65 whereby each compartment will be served by one of the pumps 22 via the respective connection 23. In this way the amount of flow to these water walled tubes connected to the respective compartments 64, may be regulated by varying the speeds of the respective pumps. This would be of advantage in case that some of the groups of wall tubes 3 are heated to a greater extent than others and would therefore require proportionately more water in their circuit. Regulation of the speed of the respective pumps may be had by regulating the valves shown in the pipes 51a which lead from the pumps, which valves can be used to control the amount of feed water passing through each pump and therefore the speed of the pump.

The pump shown in Figure 4 is substantially the same in construction as that shown in Figure 3, except that the wheel 24 is inverted and the outlet 28 of Figure 3 is omitted. In Figure 4 the outlet 40 is formed in cage 41 and the fluid leaving the wheel 24 flows downwardly through outlet 40 and joins with the water coming from the downcomer tube 21 into elbow 31 on its way

to the pump propeller 35. Optionally, the discharge of fluid from outlet 28 of Figure 3 may be connected into the elbow 31 on the inlet side of the impeller, with respect to the direction of the fluid flow.

Optionally, the boiler feed pump may be connected directly to the economizer in the usual fashion, and the discharge from the economizer connected into the header 52. The header 52 would then be directly connected to boiler drum 9. This arrangement is shown in Figure 5. Such a hook-up would be particularly applicable in case the pump of Figure 4 were employed as illustrated in Figure 6. Thus in Figure 6 the economizer discharge would connect into header 50 and each of the pipes 51 would connect to the inlet volute of pump 22. After passing through impellers 24 the feed water will discharge downwardly through port 40 to join with the water coming through downcomers 21 into the elbow 31. In this instance there would be no feed water connection to the drum. In the arrangement of Fig. 5 it is desirable to provide (as shown in Fig. 2) a valve 61 in the pipe rising from header 52, and a pipe 63 leading from the header to the pump 48, with a relief valve 62.

The secondary evaporator surface 20, shown in Fig. 2, may be advantageously applied to Figs. 5 and 6, in the event that the temperature of the water leaving the economizer 19 for the pumps 22 should be heated to a steaming temperature and found to be undesirable for use in said pumps.

While the invention is particularly applicable to high pressure boilers of the order of 1800 lbs. or more p. s. i. it may be used to advantage in any natural circulation boiler of about 900 lbs. p. s. i. or more, wherein the capacity and pressure are such, in the absence of my improved augmentation, as would compel the use of relatively large thick walled tubes.

Since numerous changes may be made without departing from the spirit and scope of the invention, it is to be understood that the above description and the drawings are to be interpreted as illustrative and not limiting.

I claim:

1. In a high capacity steam generating unit, the combination of a natural circulation boiler of the type in which the steam is generated at least in major part in a multiplicity of generally vertical boiler tubes subject to radiant heat and which has a steam and water drum, said boiler operating at a pressure of about 900 lbs. p. s. i., and upward, but short of critical pressure, a downcomer leading from the drum, a pump for augmenting natural circulation located in said downcomer, a water turbine for driving said circulation pump during steam generation, a feed water pump operating at a pressure exceeding the sum of the boiler pressure and the pressure drop through the turbine, a first line for delivering feed water from the feed water pump to the turbine inlet, and a second line for delivering feed water from the turbine outlet to the boiler at a rate equal to the rate of steam generation.

2. In a high capacity steam generating unit, the combination of a natural circulation boiler of the type in which steam is generated at least in major part in a multiplicity of generally vertical boiler tubes subject to radiant heat and which has a steam and water drum, said boiler operating at a pressure of about 900 lbs. p. s. i., and upward, but short of critical pressure, a multiplicity of downcomers leading from the

drum, a pump located in each downcomer for augmenting natural circulation, means for checking the upward flow of water in each of said downcomers, a water turbine for driving each pump during steam generation, a feed water pump operating at a pressure exceeding the sum of the boiler pressure and the pressure drops through said turbines whereby to provide discharge of water from said turbines at a pressure exceeding said boiler pressure, first lines for delivering feed water from the feed water pump to the turbine inlets, and second lines for delivering feed water from the turbine outlets to the boiler at a rate equal to the rate of steam generation.
